UNITED STATES PATENT OFFICE.

CHARLES D. HARRISON AND PARREN D. LINDSEY, OF HOMINY, OKLAHOMA.

RECEPTACLE CLOSURE.

Application filed August 2, 1927. Serial No. 210,145.

This invention relates generally to receptacle closures, and has more particular reference to a closure cap, for receptacles, such as fruit jars, vacuum bottles and the like, having an annular marginal flange to secure it to the neck of the jar or the like and provided with a central depending tubular member capable of use as a fruit depressor, or adapted to form with the closure cap, when removed from the receptacle, a cup and saucer unit for use in drinking a portion of the contents of the receptacle.

An object of the invention is to provide a device of the above kind which is simple and durable in construction and capable of ready manufacture at a nominal cost.

Other objects will become apparent as the nature of the invention is better understood, and the same consists in the novel form, combination and arrangement of parts hereinafter more fully described, shown in the accompanying drawing and claimed.

In the drawing, wherein like reference characters indicate corresponding parts throughout the several views,

Figure 1 is a fragmentary view, partly in side elevation and partly in central vertical section, of a fruit jar equipped with a closure provided with a depending tubular member in accordance with the present invention, and illustrating the tubular member in use as a fruit depressor.

Figure 2 is a bottom plan view of the closure and tubular member removed,

Figure 3 is a view somewhat similar to Figure 1, of a jar equipped with a modified form of the invention,

Figure 4 is a top plan view of the device of Figure 3 removed from the jar, and

Figure 5 is an enlarged fragmentary section, illustrating a detail of the device shown in Figures 3 and 4.

Referring more in detail to the drawing, the present invention embodies a conventional metallic closure cap, for fruit jars, vacuum bottles and the like, including a flat top wall 5 free of projections on its outer face and having an annular marginal flange 6 to secure it on the neck 7 of the jar or like receptacle 8. A tubular metallic member 9 is rigidly attached to the under side of the top wall 5 of the cap in spaced concentric relation to the flange 6, and said member 9 is open at its lower end and is of a length to extend well below the flange 6, as shown. The member 9 is also prefer-

ably of downwardly flaring form, but of a major diameter sufficiently small to pass freely through the neck 6 of the receptacle so as to be removable from the latter with the cap. It will thus be seen that the device, when removed from the receptacle, may be inverted for use as a cup and saucer unit serviceable in drinking a portion of the contents of the receptacle. Moreover, the unit will rest properly upon a table or the like due to the flat form of the wall 5, and any fluid spilled from the member 9 will be caught in the annular space in the cap between the member 9 and the rim 6.

The invention may also serve the useful purpose of a fruit depressor for preserving jars as shown in Figure 1, wherein the flange 6 is threaded to engage the threaded neck of the jar, and the member 9 holds the fruit below the surface of the liquid or syrup, whereby the tendency of the top layer of fruit to become moldy and spoiled is prevented.

In the form of the invention shown in Figures 1 and 2, the member 9 is closed at its upper end by a flat wall 10 flatly contacting the wall 5 of the cap and permanently attached to the latter by soldering or the like, as at 11.

As shown in Figures 3 to 5 inclusive, the wall 5 of the cap may have a circular central depressed portion 12 onto which the upper end of the tubular member 9 is fitted and secured. By threading the upper end of the member 9 onto the member 12, as at 13, the member 9 may be separated from the cap to facilitate thorough cleaning of these parts, and to insure against leakage between the threaded walls, the upper end of the member 9 may be formed with an annular outturned flange 14 of upwardly flaring form adapted to be flexed into firm flat engagement with the underside of the top wall 5 of the cap when the upper end of the member 9 is fully threaded onto the depressed portion 12 of the cap.

Obviously, the cup and saucer unit is especially serviceable to campers and tourists when embodied in the closure of a vacuum or thermos bottle used for carrying hot or cold drinks or beverages.

Minor changes may be made without departing from the spirit and scope of the invention as claimed.

What we claim as new is:

1. A device of the character described

- comprising a metallic closure cap for preserving jars having a flat top wall and provided with an annular marginal flange to secure it on the neck of the jar, and a tubular metallic fruit depressing member rigidly attached to the under side of the top wall of said closure cap in spaced concentric relation to said annular flange, said tubular member being open at its lower end and projecting well below said flange to form with the closure cap, when removed from the jar, a drinking cup and saucer unit for reception of a portion of the contents of said jar.
2. A device of the character described comprising a metallic closure cap for jars having a flat top wall and provided with an annular marginal flange to secure it on the neck of the jar, and a tubular metallic member rigidly attached to the under side of the top wall of said closure cap in spaced concentric relation to said annular flange, said tubular member being open at its lower end and projecting well below said flange to form with the closure cap, when removed from the jar, a drinking cup and saucer unit, for reception of a portion of the contents of said jar, said top wall of the cap having a central depressed portion onto which the upper end of said tubular member is fitted and secured.
3. A device of the character described comprising a metallic closure cap for jars having a flat top wall and provided with an annular marginal flange to secure it on the neck of the jar, and a tubular metallic member rigidly attached to the under side of the top wall of said closure cap in spaced concentric relation to said annular flange, said tubular member being open at its lower end and projecting well below said flange to form with the closure cap, when removed from the jar, a drinking cup and saucer unit for reception of a portion of the contents of said jar, said top wall of the cap having a central depressed portion onto which the upper end of said tubular member is fitted and secured.

per end of said tubular member is detachably secured.

4. A device of the character described comprising a metallic closure cap for jars having a flat top wall and provided with an annular marginal flange to secure it on the neck of the jar, and a tubular metallic member rigidly attached to the under side of the top wall of said closure cap in spaced concentric relation to said annular flange, said tubular member being open at its lower end and projecting well below said flange to form with the closure cap, when removed from the jar, a drinking cup and saucer unit for reception of a portion of the contents of said jar, said top wall of the cap having a central depressed portion onto which the upper end of said tubular member is detachably threaded.

5. A device of the character described comprising a metallic closure cap for jars having a flat top wall and provided with an annular marginal flange to secure it on the neck of the jar, and a tubular metallic member rigidly attached to the under side of the top wall of said closure cap in spaced concentric relation to said annular flange, said tubular member being open at its lower end and projecting well below said flange to form with the closure cap, when removed from the jar, a drinking cup and saucer unit for reception of a portion of the contents of said jar, said top wall of the cap having a central depressed portion onto which the upper end of said tubular member is detachably threaded and an upwardly flaring outwardly turned annular flange on the upper end of said tubular member adapted to be flexed into firm flat contact with the top wall of the cap when the upper end of said tubular member is fully threaded onto said depressed portion.

In testimony whereof we affix our signatures.

CHARLES D. HARRISON.
PAREN D. LINDSEY.
